FIREBOX CONSTRUCTION

Howard L. Miller, Cleveland Heights, Ohio, assignor to Republic Steel Corporation, Cleveland, Ohio, a corporation of New Jersey

Application April 16, 1947, Serial No. 741,741

6 Claims. (Cl. 122—58)

1

This invention relates generally to boilers and more specifically to the construction of firewalls and crown sheets for boiler fireboxes, particularly those employed in locomotive and marine type boilers, and a novel method of making such devices.

For over a century boilers of the type to which this invention relates have had fireboxes formed of inner and outer metal sheets stayed together against pressure between the sheets by stay bolts. These bolts have been applied by drilling or punching holes in the inner and outer sheets, tapping these holes, inserting threaded stay bolts therethrough and riveting the heads over. It has also been customary to employ threaded bolts and to tap the inner sheets as an additional holding means using ball end flexible bolts in the outer sheets. The inside sheet of the firewall and the crown sheet are heated by the fire within the firebox causing expansion of the inner sheet. Also, steam under high pressure is present in spaces between the inner and outer sheets tending to separate the inner sheet and outer sheet and stretch the stay bolts. As a result, when the boiler cools down the inner sheet and the stay bolts contract and distort which tends to pull the sheet away from the stay bolts and loosen the joints around the stay bolts. This results in leakage around the stay bolts and it is not uncommon for the sheets themselves to develop fatigue cracks at the stay bolt holes causing failure and necessitating replacement of sheets.

It is an object of the present invention to provide a firewall construction and a crown sheet construction which will not be subject to excessive deformation or failure in use and which will not leak due to expansion and contraction of the parts. Briefly, I attain these results in a novel firewall construction by building up the firewall from structural members in such a manner that no stay bolts are required in areas of the assembly subjected to the heat of the fire, the inner wall being imperforate. I have found that one effective method of making such a wall resides in forming a series of firewall elements from structural members such as I beams. In this construction apertures are punched in the webs of the I beams for water circulation, and the flanges of the I beams are welded together edge to edge to form a continuous wall. The I beams are vertically disposed and the upper end of the firewall so formed is welded to the crown sheet structure.

Generally speaking, I make a novel crown sheet by severing the webs of I beams to form longitudinal members of T cross-section, or preferably

2

by utilizing rolled section of T formation. I then weld stay bolt anchoring means to the vertical legs or webs of the T sections and weld flanges edge to edge to form a continuous crown sheet firewall. A firebox made according to these principles is highly resistant to deformation and deterioration due to action of the heat, has no tendency to leak due to loosening around the apertures for the stay bolts and is of generally superior and long lasting construction.

Another object lies in the provision of a firewall made according to the general principles outlined above but of tapering cross-section to provide a smooth juncture with the crown sheet and roof sheet.

Still another object of my invention resides in the provision of novel and effective means for anchoring stay bolts to the crown sheet without requiring piercing of the crown sheet.

20 A further object of my invention resides in the provision of a firebox which has the inner wall formed of heat resistant metal such as ferritic chrome steel and the outer wall of a more economical metal such as mild steel or structural steel, the structure being made in accordance with the principles outlined above and being relatively economical to manufacture.

These and other objects of my invention will be apparent to those skilled in the art as the following description proceeds.

30 In the drawings:

Fig. 1 is a longitudinal section through a locomotive firebox embodying a preferred form of my invention;

35 Fig. 2 is a fragmentary perspective view of a firewall made in accordance with a preferred form of my invention;

Fig. 3 is a partial cross-section through a firebox produced in accordance with the preferred form of my invention;

40 Figs. 4 to 7 show means employed for attaching stay bolts to the crown sheet in accordance with my invention;

Fig. 8 is a partial cross-section through a firebox showing a modified form of firewall that is tapered and merges with a curved crown sheet section constructed similarly to the firewall;

Fig. 9 is a modified form similar to that shown in Fig. 8 except that the firewall is not tapered;

50 Fig. 10 is a modified form showing a modified crown sheet section joined to the firewall;

Fig. 11 illustrates a form similar to that shown in Fig. 9 wherein the structural member firewall and crown sheet section are welded to a conventional crown sheet and roof sheet; and

55 Fig. 12 illustrates a fragmentary section

through a composite firewall wherein the elements exposed to the fire are heat-resistant metal.

Referring to Fig. 1, which is a simplified section through a locomotive boiler illustrating the over-all relationship of my novel firewall, radius sheet and crown sheet, the boiler B includes the crown sheet C, the radius sheet R, and the firewall W which units are joined together as will be hereinafter described. The lower edge of the firewall is welded to the foundation ring 10 and the lateral elements 11 of the ring form the foundation for the back boiler head 12 and the throat sheets 14. The roof sheet 13 is preferably of conventional construction as is the back tube sheet 15.

As shown in Figs. 2 and 3, the firewall W made in accordance with the principles of this invention is formed from a plurality of vertically disposed structural channel members 20 preferably formed from I beams. In order to provide for water circulation I cut or punch out a series of apertures 22 in the webs of the I beams. The remaining portions of the initially imperforate web form a series of webs 23 that provide integral tie members between the two flanges. I then weld the flanges of the I beams together edge to edge as at 24 and I prefer to employ a backing plate 25 previously tacked on to one of the I beams before the welding operation. The lower edges of each flanges are welded to the foundation ring 10 as at 26 and 27, and in order to reinforce the structure at this junction one row of stay bolts 28 may be provided. I may attach the upper edge of the firewall so formed to the radius sheet R by welding as at 33. I form the I beams to provide an extension 29 at the outer wall which I weld to the roof sheet 13 as at 32. In this manner the lower stay bolt 31 for the radius sheet passes through an aperture 30 in the outer portion of the firewall and serves to additionally hold these parts together against pressure between the walls.

A firewall formed in this manner does not rely upon stay bolts to maintain the parts in assembled relation against pressure and high heat so that the expansion due to heating and cooling will not cause leaking. The single row of stay bolts 28 adjacent the foundation ring 10 is below the grate surface, consequently these bolts are always covered with water and will cause no trouble. The web portions 23 are integral with the inner and outer walls, and serve not only to resist wall separation but serve to rigidly maintain the inner wall in position relative to the outer one and prevent deformation and distortion in service.

The neutral axis of the remaining webs 23 are provided with through apertures or tell-tale holes 23a. Not only do these apertures increase the heat transfer to the water, but if one or more of the remaining webs 23 fracture at the welds or otherwise, such fracture will be indicated by leakage of water or escape of steam from within the fire wall.

A preferred form of a crown sheet C, radius sheet R and stay bolt assembly is shown in Figs. 3 to 7. To produce the crown and radius sheets I use a plurality of T-shaped sections or beams 40. The webs are then slit as at 41 to provide a plurality of generally radially extending ears 42. In the form shown in Figs. 4 and 5 stay bolt anchors or sockets are welded to ears 42. I prefer to form the anchor in the form of a neck member 43 welded to each ear

and an integral socket member 44 for receiving the threaded shank of a stay bolt 45. The stay bolt is adjustably tensioned against the roof sheet 13 by means of a nut assembly 46 which provides a seal and tensions the bolt. The details of the construction of the assembly 46 may be varied in accordance with standard practice and form no part of the present invention.

A modified form of attaching means for the stay bolt is shown in Figs. 6 and 7 wherein a pair of ears 50 are assembled in a slot 51 in the shank of each stay bolt 45, the ears forming a clevice for encompassing the ears 42 of the crown sheet web. Bolts or other fasteners 52 may be employed to secure the stay bolts to the crown and radius sheet web. A crown and radius sheet so manufactured is imperforate and shows no tendency to leak or deform in service. By slotting the webs as at 41 to form the ears 42 I provide a degree of flexibility and also insure that each stay bolt assumes its share of the load.

If a water firewall which gradually increases in thickness from the foundation ring to the junction which the crown sheet is desired, I may employ the structure shown in Fig. 8. The I beam members 60 of the firewall W have a tapered piece removed from the web 62 whereupon the webs are welded together as at 63 to provide a firewall of generally tapered cross-section. When the spacing between the inner and outer walls exceeds the depth of the I beam to be employed in the construction, I sever the webs of I beams 61 to form sub-members the flanges of which are to be inner and outer walls 65 and 66 and weld to the severed web sections a plurality of gusset plates 67 to form composite members, the gussets being dimensioned so that the firewall merges smoothly with the radius sheet R and crown sheet C and the roof sheet 13. After these web sections have been severed and the severed webs have been welded together, apertures are cut in the resultant composite web for water circulation through the firewall. T sections of suitable size may replace one of the sub-members. The radius sheet section thus formed is welded to the tapered firewall section as at 69, to the roof sheet as at 70 and the crown sheet formed of longitudinal members 40 as at 71.

The form shown in Fig. 9 has the radius sheet section R formed of gusseted I beams or T sections like that shown in Fig. 8 but employs the parallel side wall firewall W formed of I beams 20 similar to that described in connection with Fig. 3. In the constructions just described no stay bolt is employed where the crown sheet is welded to the firewall.

In the form shown in Fig. 10, crown sheet C 60 is welded as at 74 to a modified radius sheet section 75. This includes a plurality of transversely extending members of the T section 76, the webs of which are slit to provide ears 71 for the attachment of stay bolts 78 and the lower end thereof welded to the firewall W as at 79. This provides an effective means of joining the crown sheet to the firewall. The edges of the T-shaped members 76 are welded together to present an imperforate wall to the firebox as described in connection with the assembly of members 40 of the crown sheet.

Fig. 11 shows a modified form wherein the straight walled members 20 forming the firewall W are welded as at 69 to the gusseted I beam or T members 65 and 66 similar to the

construction described in Fig. 9. However, in this construction a conventional crown sheet section 80 is employed and is welded to the radius sheet section as at 81. The roof sheet is welded to the flange on member 66 as at 82. The gusseted radius sheet section here serves to strengthen the roof section of the firewall because of its rigid and non-distortable construction.

It is desirable to form the walls that are subjected to the heat of the fire of a heat-resistant metal such as boiler steel, firebox steel or the like. However, this steel is relatively expensive as compared to the cost of mild steel and in Fig. 12 I show a composite firewall structure wherein the advantages of heat resistance and economy are combined in one structure. To produce the firewall illustrated in Fig. 12, I sever the webs of one set of structural members such as I beams made of heat-resistant steel and sever the webs of an equal number of such members made of mild or structural steel. For example, in Fig. 12 the members 90 may be considered to be of mild structural steel and the members 92 to be of heat-resistant steel. Before the firewall is fabricated the severed webs 91 of the mild steel members are welded to the severed webs 93 of the firebox steel members as at 94. Then the edges of all flange members of the composite I beams so formed are welded together as at 95 with the heat-resistant elements all welded together. This forms a firewall of rigid imperforate construction like that previously described but since only the inner wall need be of heat-resistant material there is a great saving in cost. Of course, the composite webs formed in this manner may be perforated as previously described for water circulation.

I contemplate that the composite structure shown in Fig. 12 may be adapted to the assemblies illustrated in the other figures. Although I prefer to employ I beams as the elements of the firewall and crown sheet construction, I could form firebox elements having characteristics like that described by severing the webs of channel irons or utilizing T sections and welding the flanges together edge to edge.

Unless otherwise qualified, the terms "channel member" or "channeled members" as found in the specification and claims is intended to include any structural member having opposed flanges joined by a web which member can be used to practice the invention, such as C-shaped channel irons, I-beams, H-beams, and the like. All of these elements are characterized by a structure involving opposed flanges joined by a web and obviously all may be employed to practice the broader aspects of the invention.

I contemplate that special structural shapes may be rolled for use in my construction. For example, an I beam could be rolled having one flange thicker than the other, which flange would then be employed as the outer flange or wrapper sheet of the firewall without materially increasing the weight.

These and other modifications may be made without departing from the spirit of my invention and I contemplate that I do not wish to be limited to the illustrated embodiments except as may be set forth in the appended claims.

What is claimed is:

1. The method of forming a unitary firebox section for a boiler comprising longitudinally severing the webs of a set of channeled structural steel members, severing the webs of a second set of channeled members composed of heat re-

sistant steel, welding the resulting severed webs of one set of members to the corresponding severed webs of the other set, forming apertures in the resultant composite web for water circulation, and welding the flanges of each set together to form a firewall.

2. The method of making a boiler wall comprising the steps of severing the webs of channeled members to form sub-members, disposing gussets between opposed edges of the severed webs of opposed pairs of sub-members, welding the gussets to said opposed web edges to form composite members, aperturing the webs of said composite members, and welding the flanges of said composite members together edge-to-edge.

3. In a boiler, a unitary firewall section built of paired elongated elements, each pair of elements comprising inner and outer spaced and parallel members forming a hollow wall portion, each member having web means extending perpendicularly with respect to the member but interiorly with respect to the wall portion, the web means of each said pair being welded together edge-to-edge, with the exterior sides of said paired elements facing oppositely to form composite channel members with interior and exterior wall surfaces, said inner members being welded together edge-to-edge and said outer members being welded together edge-to-edge to form the firewall section, said firewall section having a plurality of tell-tale holes, said holes extending thru both members of a pair and thru the associated web means whereby fracture of the web means will be indicated by escape of fluid from within said firewall and through said holes.

4. In a boiler, a first wall section built up of generally vertically disposed paired elongated elements, each pair of elements comprising inner and outer wall portions and connecting members, the inner wall portions being welded together edge-to-edge, a second wall section formed of a second series of vertically disposed wall portions having curved, spaced, diverging inner and outer flanges and integral web members, gussets welded between said web members, said curved flanges being welded together edge-to-edge to form a leak-proof wall, said second series of elements being end welded to form a continuation of said wall vertical section, and a third section welded to said second section and comprising a plurality of elongated elements, said last-mentioned elements having inner flanges welded together edge-to-edge to form a wall, integral web means extending outwardly from said last mentioned flanges, an outer sheet spaced from said last mentioned wall and a plurality of stay bolts extending between said web means and said outer sheet, the elements of said third section being transversely disposed relative to those of said other sections.

5. In a boiler, a curved wall section formed of a series of generally vertically disposed elements having curved, spaced, diverging inner and outer flanges and integral web members, gussets welded to and between said web members, said curved flanges being welded together edge-to-edge to form a leak-proof wall, and another wall section welded to said curved wall section and comprising a plurality of elongated members, each elongated member having an inner flange welded together edge-to-edge to the inner flange of an adjacent elongated member to form an inner wall, integral web means extending outwardly from the adjacent flanges of said elongated mem-

bers, an outer sheet spaced from said inner wall, and a plurality of stay bolts extending between said web means and said outer sheet, the elongated members of said other section being disposed perpendicular to the generally vertically disposed elements of said curved section.

6. In a boiler, a curved wall section comprising a plurality of relatively straight, elongated elements, each element having an inner flange and an integral outwardly extending web, said flanges being welded together edge-to-edge to form an inner wall, an outer sheet spaced from said inner wall, a plurality of stay bolts extending between said web and said outer sheet, the members of said wall section being longitudinally disposed with respect to the boiler.
